UNITED STATES PATENT OFFICE.

JOHN A. STUMPENHORST, OF WILKINSBURG, PENNSYLVANIA, ASSIGNOR TO WESTINGHOUSE ELECTRIC & MANUFACTURING COMPANY, A CORPORATION OF PENNSYLVANIA.

IGNITION BREAKER CONTACT.

1,382,870.

Specification of Letters Patent. Patented June 28, 1921.

Application filed July 5, 1919. Serial No. 308,710.

To all whom it may concern:

Be it known that I, JOHN A. STUMPENHORST, a citizen of the United States, and a resident of Wilkinsburg, in the county of Allegheny and State of Pennsylvania, have invented a new and useful Improvement in Ignition Breaker Contacts, of which the following is a specification.

My invention relates to ignition mechanisms and particularly to circuit breakers therefor.

The object of my invention is to provide a simple and inexpensive device for so adjusting the circuit-breaker contacts that they shall be parallel to each other over their entire coöperating surfaces.

In assembling circuit breakers for ignition apparatus, it is essential that the coöperating contacts shall be in engagement over their entire surfaces, and, where no adjusting means is provided for the stationary contact arm, it may be necessary to bend the resilient member or to disassemble the breaker parts and reassemble with different parts in order to insure exact parallelism of the coöperating surfaces of the contacts.

In practising my invention, I provide the stationary contact arm with two coöperating semi-spherical balls and seats held by a clamping bolt, the semi-spherical balls being provided with a circular opening therethrough somewhat larger than the diameter of the body of the clamping bolt.

In the single sheet of drawings, Figure 1 is a top plan view of the device embodying my invention; Fig. 2 is a side elevation thereof, and Fig. 3 is an enlarged view, partly in section and partly in side elevation, of the particular device embodying my invention.

Referring to Fig. 1, a supporting plate 10 of usual construction is provided with a circular opening 11 at its center in which is placed a rotatable shaft 12. The shaft 12 is driven, in any approved manner, by a gas engine (not shown) with which the ignition mechanism is to be used, and the plate 10 is mounted in any suitable position and manner thereon. The shaft 12 has an extension 13, at its upper end, which is provided with a plurality of cam faces 14 that are usually equal, in number, to the number of cylinders of the gas engine with which the device is to be associated. The cam faces 14 engage a resilient member 15 carrying a contact 16,

the member 15 being suitably mounted on the supporting plate 10 and insulated therefrom according to standard practice in the art.

The coöperating contact 17 is mounted at one end of an arm 18, the other end of which has a circular opening 19 drilled therethrough. Two semi-spherical members 20 are provided, each having a circular opening 21 drilled therethrough that is somewhat larger, in diameter, than the diameter of the body of a clamping bolt or screw 22. Two coöperating seat members 23 of circular contour each having one flat face and a semi-spherical depression in the other face, are also provided to coöperate with the semi-spherical members 20.

The arm 18 is placed between the flat faces of the semi-spherical members 20 which are, in turn, placed between the coöperating seat members 23 and are then clamped against the plate 10 by means of the bolt 22. The bolt 22 is made somewhat larger than would otherwise be necessary, in order to insure that the arm 18 shall not be moved when the device is in operation, and the opening 19 in the arm 18 is made somewhat larger than the diameter of the body of the clamping bolt 22 to give a clearance, for a purpose to be herein-after described.

Referring particularly to Fig. 3, it is apparent that the arm 18 may be moved to the right or to the left by a distance equal to the clearance between the body of the bolt 22 and the circular opening 19 in the arm 18 without changing the distance from the contact point 17 to the surface of the supporting plate 10. If it becomes necessary to change this distance slightly in order to line up the coöperating contacts 16 and 17, the arm 18 and the two semi-spherical members 20 may be moved in the seat members 23 by an amount determined by the clearance between the circular opening 21 in the members 20 and the diameter of the body of the bolt 22. If it becomes necessary to adjust in the direction of the line x—x in Fig. 1 at right angles to the surface of the plate 10, this may be done with equal facility by tilting the arm 18 and the members 20 in the desired direction an amount limited by the clearance between the opening 21 in the members 20 and the diameter of the body of the bolt 22. It will be seen that adjustments of the arm 18 may be made with ease

and without disturbing any other parts of the ignition mechanism.

Various modifications may be made in the device without departing from the spirit and scope of my invention, and I desire that only such limitations shall be imposed as are indicated by the prior art or are specifically set forth in the appended claims.

I claim as my invention:

- 10 1. In an ignition mechanism, the combination comprising two coöperating contact members, an arm for supporting one of said contact members, two semi-spherical members disposed on opposite sides of said arm and coöperating seats therefor, and clamping means for holding said arm in position between said members.
- 15 2. In an ignition mechanism, the combination with a pair of coöperating contact members, of a lever arm for supporting one of said contact members, and means for effecting universal angular adjustment of said arm.
- 20 3. In an ignition mechanism, the combination with a pair of coöperating contacts, of means on which one of said contacts is

mounted, and a clamping member for said mounting means that permits universal angular adjustment of said mounting means and contact, and also adjustment of said means and said contact in a plane perpendicular to said clamping member.

4. In an ignition mechanism, the combination with a pair of coöperating contacts, and an arm at one end of which one of said contacts is mounted, of clamping means for the other end of said arm that permits universal angular adjustment of said contact.

5. In an ignition mechanism, the combination with a pair of coöperating contacts and an arm at one end of which one of said contacts is mounted, of clamping means for the other end of said arm comprising a plurality of semi-spherical members and co-operating seats therefor and a retaining bolt to permit universal angular adjustment of said contact.

In testimony whereof, I have hereunto subscribed my name this 1st day of July, 1919.

JOHN A. STUMPFENHORST.
